UNITED STATES PATENT OFFICE.

GEORGE H. LOFLAND, OF BROOKLYN, NEW YORK.

MOUNTING FOR LENSES.

1,262,528.

Specification of Letters Patent.

Patented Apr. 9, 1918.

Application filed May 29, 1917. Serial No. 171,693.

To all whom it may concern:

Be it known that I, GEORGE H. LOFLAND, a citizen of the United States, and a resident of the city of New York, borough of Brooklyn, in the county of Kings and State of New York, have invented a new and Improved Mounting for Lenses, of which the following is a full, clear, and exact description.

10 Among the principal objects which the present invention has in view are: to avoid breakage of lenses when mounting the same in a handle; to reduce the cost of the mounting; and to simplify the operation of providing lenses with service handles.

Figures.

Figure 1 is a side view of a lens and mounting therefor constructed and arranged 20 in accordance with the present invention, part of the figure being cut away to show in section the interior construction;

Fig. 2 is a detail view in perspective showing a mounting band constructed and arranged in accordance with the present invention, said band being shown in its opened position;

Fig. 3 is a similar view showing a holding frame in closed position with a binding ring therefor constructed and arranged in accordance with the present invention;

Fig. 4 is a detail view on an enlarged scale showing end fragments of the holding frame and in the form assumed thereby prior to assembling the same;

Fig. 5 is a detail view showing in perspective the binding ring employed for holding the ends of the framing band together.

Description.

40 As seen in the drawings, the lens 10 is framed by a band 11.

Lenses of the character shown are sometimes irregular in shape and dimension. 45 For this reason it is expedient to provide some means of connecting the ends of the band which is adaptive to these conditions. To this end, the present invention employs reduced ends 12. The ends 12 are integral 50 with the band 11, and being centrally located in said band, the groove 13 formed therein is also formed in said ends 12.

In forming the band 11, a continuous metal strip of proper width has routed 55 therein the groove 13. Subsequently the strip is cut into separate pieces of desired

length and the ends 12 shaped as shown. When shaping the ends 12, said ends are severed from the body of the band 11, by short cuts 14. The cuts 14 permit the ends 60 12 to be turned back approximately perpendicular to the ends of the said band. As seen best in Fig. 1, this results in forming a space 15 between the inner extremities of the said ends 12 when the outer extremities 65 of the said ends are engaged. The combined effect of the ends 12 is to form a tapered extension from the ring-like band 11, said tapered extension operating in conjunction with the coil spring retaining ferrule 16 to 70 hold the ends of the band together to form a continuous ring.

The ferrule 16 is a short section of spring wire coil. When the ferrule 16 is slipped over the joined ends 12 and forced to the 75 inner extremities thereof, the taper of the said joined ends expands the convolutions of the inner end of the ferrule, which yields to relieve the contracted strain on the band 11, which otherwise might operate to injure 80 the lens 10.

After the ferrule 16 has been disposed as shown in Figs. 1 and 3 of the drawings, the tube 17 is adjusted to infold the said ends 12 and ferrule 16. In practice, the tube 17 85 loosely fits the ferrule 16. Solder or plastic setting cement is then poured into the tube 17 to embed the ferrule 16 and ends 12, entering the interspaces of the coil forming the ferrule and also entering the gap 15 between the ends 12. The surface adhesion 90 of the solder to the tube 17 is sufficient to maintain the said tube permanently engaged with the said ends and binding ferrule therefor.

When the solder 18 above referred to congeals, the handle 19 and finishing ferrule 20 are adjusted to the tube 17, being adhered thereto by any suitable means.

Claims.

1. A mounting as characterized comprising a centrally grooved framing band having integral reduced ends extending from the joined ends of said band approximately 105 perpendicular to the connected portions of said band; and means for holding said ends in juxtaposed relation and for exerting a closure strain upon said band, said means embodying a cylindrical member, a tube infolding said member, and a filling for said tube.

2. A mounting as characterized comprising a centrally grooved framing band having integral reduced ends extending from the joined ends of said band approximately 5 perpendicular to the connected portions of said band; and means for holding said ends in juxtaposed relation and for exerting a closure strain upon said band, said means embodying a corrugated ferrule adapted for 10 extension over said ends to draw the terminals of said band toward each other, a tube for infolding said ferrule, and a suitable cement filling said tube in surrounding relation to said ferrule.
- 15 3. A mounting as characterized comprising a pliable metal band having reduced ends integrally formed with and extended from the terminals of said band, said ends being partially severed from said band to 20 form an angle therewith removed from the terminal extremities of said band; and a resilient cylindrical member fitting said ends for exerting a pulling strain thereon for drawing the terminals of said band in juxtaposition.
- 25 4. A mounting as characterized comprising a pliable metal band having reduced ends integrally formed with and extended from the terminals of said band, said ends being partially severed from said band to 30 form an angle therewith removed from the terminal extremities of said band; and a spring coil ferrule adapted for extension over said
- over said ends for drawing the terminals of said band in juxtaposed relation. 35
5. A mounting as characterized comprising a pliable metal band having reduced ends integrally formed with and extended from the terminals of said band, said ends being partially severed from said band to 40 form an angle therewith removed from the terminal extremities of said band; a spring coil ferrule adapted for extension over said ends for drawing the terminals of said band in juxtaposed relation; and means for permanently uniting said ends and said ferrule, said means embodying a suitable cement intimately surrounding and infolding said ends and said ferrule. 45
6. A mounting as characterized comprising a pliable metal band having reduced ends integrally formed with and extended from the terminals of said band, said ends being partially severed from said band to 50 form an angle therewith removed from the terminal extremities of said band; a spring coil ferrule adapted for extension over said ends for drawing the terminals of said band in juxtaposed relation; and means for permanently uniting said ends and said ferrule, 55
- 60 said means embodying a suitable cement intimately surrounding and infolding said ends and said ferrule; and a tube surrounding said ends, ferrule, and cement uniting the same.

GEORGE H. LOFLAND.
